UNITED STATES PATENT OFFICE.

CHARLES P. NICHOLS, OF CRANSTON, RHODE ISLAND.

SWEEP-STRAP FOR LOOMS.

SPECIFICATION forming part of Letters Patent No. 737,266, dated August 25, 1903.

Application filed December 12, 1901. Serial No. 85,642. (No model.)

To all whom it may concern:

Be it known that I, CHARLES P. NICHOLS, a citizen of the United States, residing at Cranston, in the county of Providence and 5 State of Rhode Island, have invented a new and useful Improvement in Sweep-Straps for Looms, of which the following is a specification.

This invention has reference to a device de- 10 signed to take the place of leather sweep straps or lugs used on looms.

The invention consists in the peculiar and novel construction and the combination whereby the power of the sweep-strap is 15 brought to bear more centrally on the picker-stick than heretofore, as will be more fully set forth hereinafter.

The object of the invention is to produce a 20 more durable sweep strap or lug which can be adjusted lengthwise.

Figure 1 is a front view of a loom, showing my improved sweep straps or lugs in connection with the sweep-arms and picker-sticks. Fig. 2 is a plan view of my improved sweep- 25 strap, showing the buffers and picker-stick in section. Fig. 3 is a side view of the sweep-strap with the loop partly broken away and showing the means of adjustably supporting the sweep-strap on the picker-stick. Fig. 4 is a detail sectional view through the center of 30 the loop, showing the means of adjusting and securing the loop to the sweep-arm. Fig. 5 is a cross-sectional view through the loop of the sweep-strap, showing the buffers sup- 35 ported on the loop and one of the buffers ex- tended upward to form a support for the sweep-strap on the picker-stick. Fig. 6 is a sectional view through the end of the sweep- arm and loop of the sweep-strap, showing the 40 U-shaped bolt and bar for securing the ends of the sweep-strap to the sweep-arm.

In the drawings, A A indicate the power-arms of a loom, operated in the usual way to throw a shuttle by the picker-sticks B B and the sweep-arms C C. The sweep-arm C, I make preferably of wood with the hole c at 45 its inner end to pivotally connect it to the end of the power-arm A. On the outer end I adjustably fasten the metal loop c' with the 50 flattened ends c² to the sweep-arm by the U-shaped bolt c³ and the bar c⁴. The flattened ends c² are provided with corrugations

or grooves c⁵ on their inner and outer faces. The U-shaped bolt c³ has on the inner side of its closed end the V-shaped ribs c⁶, corresponding to the grooves on the flattened loop ends c² and on its outer ends the nuts c⁷. The bar c⁴ has two holes for the U-shaped bolt c³ and has the ribs c⁸ on its inner face. At the end of the metal loop c' I support the 60 buffers D on the loop by the holes d d. (Shown in Fig. 5.) The buffer D is made of three or more flat pieces of leather or other suitable material. The inner and outer pieces d d' are approximately square. The center piece 65 d² is extended upward and narrowed in width to form the strap d³ with the holes d⁴ to fasten it to the picker-stick by the screw d⁵. The buffer D, formed by the plates d d' and d², is loosely mounted on the loop c' intermediate 70 the picker-stick.

To adjust the sweep plug or loop lengthwise, I loosen the nuts c⁷ c⁷ on the U-shaped bolt c³. The loop c' can then be moved longitudinally into the position required and locked by 75 tightening the nuts c⁷ c⁷ on the bolt c³. This forces the ribs c⁶ on the closed end of the bolt c³ and the ribs c⁸ on the bar c⁴ into the grooves c⁵ on the outside of the flattened loop ends c², clamping the ends c² of the loop between the 80 sweep-arm, the closed end of the bolt c³, and the bar c⁴ and forcing the wood of the picker-strap into the grooves c⁵ on the inner side of the ends c², thus securely fastening the loop to the sweep-arm. To adjust the position of 85 the sweep-lug on the picker-stick for different weights of cloth, I provide the upwardly-extending buffer-strap d³ with a number of holes d⁴, and by means of these holes adjustably fasten the strap d³ to the picker-stick by 90 the screw d⁵.

By this construction the bearing of the sweep strap or lug on the picker-stick is at all times uniform with the pull of the sweep-arm. The buffers above and below the rounded 95 loop or lug will bend backward according to the position of the picker-stick. The loop or lug being of metal will last for a very long time, while the buffers may be readily renewed as they become worn.

Having thus described my invention, I claim as new and desire to secure by Letters Patent—

1. A sweep-strap, having a loop formed

from a round piece of metal with flattened ends adjustable lengthwise on the sweep-arm and surrounding the picker-stick, corrugations formed on each side of both of the flattened ends of the loop, a U-shaped bolt extending through the sweep-arm provided with corrugations on the part extending over the end of the loop, and a bar provided with corrugations on one side, nuts on the ends of the bolt outside the bar for clamping the flattened ends of the loop between the closed end of the bolt, the inside of the bar and the sweep-arm, as described.

2. In a sweep-strap for looms, the combination with the power-arm A and the picker-stick B, a sweep-arm C having the buffer D at its outer end and the hole c at its inner end to pivotally connect it to the picker-arm, the loop c' with flattened ends c² having the

corrugations c⁵ on their inner and outer faces, 20 the U-shaped bolt c³ with the ribs c⁶ and the bar c' with the ribs c⁸ corresponding to the corrugations on the loop ends c², the nuts c⁷ on the ends of the bolt c³ and outside the bar c', the buffer-plates d' d' and d² with the holes 25 d to support the buffer-plates on the loop c', the upwardly-extending strap d³ from one of the buffer-plates having the holes d⁴ and the screw d⁵ to adjustably fasten the strap to the picker-stick, as described.

In testimony whereof I have signed my name to this specification in the presence of two subscribing witnesses.

CHARLES P. NICHOLS.
